ATTORNEY

UNITED STATES PATENT OFFICE.

ELISA VON S. S. BLUM, OF DALLAS, TEXAS.

HOSIERY SPAT.

Application filed March 10, 1922. Serial No. 542,781.

To all whom it may concern:

Be it known that I, ELISA VON S. S. BLUM, a citizen of the United States, residing at Dallas, in the county of Dallas and State of Texas, have invented certain new and useful Improvements in Hosiery Spats, of which the following is a specification.

This invention relates to new and useful improvements in hosiery and pertains more particularly to a legging or spat to be worn underneath the hosiery as a protection to the feet and ankles, without necessitating the use of a larger shoe than is ordinarily worn, the object being primarily to provide such protection when fancy "open work" or thin hosiery is worn, in particular, although it aims to provide a protection to this part of the feet and limbs in a general way and it should be understood that the invention is not limited in this extent nor to any color. Spats of flesh color are preferred for fancy, "open work" or thin hosiery.

The invention will be more fully understood by reference to the following description, taken in connection with the accompanying drawing forming part hereof in which—

Figure 1 is a view of the spats in position on a foot.

Figure 2 is a side elevational view of one of the spats removed from the foot and illustrating more clearly the form of construction.

Figures 3 and 4 are a longitudinal and a cross sectional view, respectively, of the spat, taken on lines 3—3 and 4—4 of Figure 2.

Referring more in detail to the drawings,

1 denotes the spat or legging made of any kind of material, preferably knitted goods, and by preference of flesh color, in position on the foot 2. The part 3 of the spat is placed over the instep and is provided on the lower edge thereof with straps 4—4 formed in one piece with the body of the legging or spat, or may be secured in any preferred way thereto. The straps 4—4 pass under and around the foot and retain the spats in position. It should also be understood that the leg portion 5 may be longer or shorter according to requirements. Where hosiery of thin texture or of open work are worn the flesh colored spat will not be detected and will permit the artistic and neat appearance of the hosiery to be displayed, at the same time affording protection to the feet and legs. The front strap 4, assists in holding down the front portion when the stocking is drawn over the same, and the rear strap holds the angle engaging part in position.

What is claimed is—

A spat formed for wear on the foot and leg beneath the hosiery and having a body engaged with and about the ankle and over the top of the front part of the foot, and a pair of spaced members connected to the sides of the body, one of said members located beneath the ankle engaging portion and the other beneath the front foot-engaging portion.

In testimony whereof I have signed my name to this specification.

ELISA VON S. S. BLUM.
